UNITED STATES PATENT OFFICE.

NICHOLAS PSZYSTAS, OF WESTFIELD, MASSACHUSETTS.

EXERCISER.

1,133,746.

Specification of Letters Patent. Patented Mar. 30, 1915.

Application filed April 9, 1914. Serial No. 830,689.

To all whom it may concern:

Be it known that I, NICHOLAS PSZYSTAS, a citizen of the United States of America, residing at Westfield, in the county of Hampden and State of Massachusetts, have invented a new and useful Exerciser, of which the following is a specification.

My invention relates to improvements in exercising apparatuses, and resides in an apparatus, device, or machine which consists essentially of upper and under supports for the person using the exerciser, revoluble members to carry said supports through circular paths centering on the axes of said revoluble members, a fan operating simultaneously with the other movable parts, and means to actuate or drive the rotary elements without the assistance of the person in the machine, all as hereinafter set forth.

20 The object of my invention is to provide an apparatus of the class mentioned above, which is highly efficient in exercising and developing the muscles, lungs, and other parts of the human body to a degree that is lastingly invigorating, strengthening, and healthful, such apparatus being simple in construction and operation, strong and durable, and practicable in all respects.

This apparatus or exerciser requires but little floor space, and is compact as a whole, so that it can be set up and used in any room of ordinary size.

As a means for aerating, exercising, expanding, and strengthening the lungs, my machine is especially and peculiarly well adapted.

Other objects and advantages will appear in the course of the following description.

I attain the objects and secure the advantages of my invention by the means illustrated in the accompanying drawings, in which—

Figure 1 is a front elevation of a practical form of embodiment of my invention; Fig. 2, a transverse vertical section through the same, the shoulder-brace strap being omitted; Fig. 3, a front elevation of a modified form of the exerciser, and, Fig. 4, a transverse vertical section through the lat-

50 ter.

Similar numerals refer to similar parts throughout the several views.

The two constructions of the exerciser herein shown and particularly described are to be considered as practical types which are susceptible to such modification or change as may upon occasion be required in order to meet varying conditions, wherefore I do not desire or intend too closely to confine or restrict myself to such types.

60 A suitable frame is provided for either type of my exerciser, which frame consists of a base 1, base blocks 2 and 3, spaced uprights 4 and 5 rising from the block 2, spaced uprights 6 and 7 rising from the block 3, and a bar 8 connecting said uprights 5, 6 and 7 at the top.

Referring now to the apparatus illustrated in the first two views, it will be observed that a pair of shafts 9 is suitably journaled in the uprights 4 and 5, one of such shafts being directly above the other and each being provided at its inner end with a rigidly attached crank-arm 10, and that a pair of longer shafts 11 is suitably journaled in the uprights 6 and 7, each of said last-mentioned shafts being axially in line with one of said shafts 9, and also provided at the inner end with a rigidly attached crank-arm 10. The ends of the crank-arm 10, in each pair, that are most remote from the supporting shafts 9 and 11, are rigidly connected by means of a rod 12. Loosely mounted on the lower rod 12 is a foot support 13, and loosely mounted on the upper rod 12 is a hand roller or support 14. Each shaft 11 projects some distance beyond the outside of the upright 7, and a crank 15 is rigidly attached to the outer end of such projecting part. Secured to each shaft 11, between the uprights 6 and 7, is a sprocket-wheel 16, and a sprocket-chain 17 connects the two sprocket-wheels. By means of the sprocket-wheels 16 and the sprocket-chain 17 the supports 13 and 14 are maintained in the same position relative to each other, or the two pairs of crank-arms 10 are caused to assume always the same or corresponding angles to a given plane, and both shafts 11 and connected movable parts can be driven by means of either crank 15.

A pulley 18 is secured on one of the shafts 11, the lower one in this case, to which a motor may be belted for driving the mechanism.

In order to make the apparatus adjustable so that it will fit persons who differ in height and in other dimensions, a plurality of bearing openings may be made in the uprights 4-5 and 6-7 for the shafts 9 and 11, two sets of such supplementary openings appearing at 19, in Fig. 2, and a plurality of openings may be provided in the crank-arms 10 for the rods 12, as shown at 20. In this manner may be obtained a sufficiently wide range of adjustment for all practical purposes.

A shoulder-brace strap 21 may be provided if desired, the same being attached at the ends to the roller or support 14.

A fan 22 has a shaft 23 which is suitably journaled in the uprights 5, 6 and 7 just below the top bar 8. The shaft 23 with the fan 22 is driven at a sufficiently high rate of speed from the upper shaft 11, through the medium of a large pulley 24 on said last-mentioned shaft, a small pulley 25 on said fan shaft, and a connecting belt 26. It is clear from the foregoing that the motion imparted to the upper shaft 11 is transmitted to the fan 22, in consequence of which a breeze is created for the benefit and comfort of the person using the exerciser, and a draught or circulation of air produced that is sufficient to supply such person with all the fresh air he can possibly take into his lungs. The fan 22 is located above the head of the person using the apparatus, or over a horizontal plane above which such person's head does not pass, but during the exercising process the head approaches said fan, passes through the more violently agitated air nearer said fan, and then recedes or passes farther away, to again approach and repeat the operations or motions on the cycle as often as may be desired or expedient.

In practice, a person takes his position in the machine, with his feet on the foot-board or support 13, the strap 21 around his shoulders, and his hands grasping the roller or support 14, and one or more assistants operate the cranks 15, or a motor may be used in place of the assistant or assistants. The shafts 9 and 11 are now rotated and carry with them the crank members 10 and 12. Thus the person taking the exercise is carried bodily through an orbital path which assumes an elliptical form, while his hands and feet are describing complete circles or passing through circular orbits. Practically all the muscles of the body in general are brought into play during the operation of the machine, the action of the heart and the circulation of the blood are accelerated, respiration is increased, and a

stimulating and beneficial effect on practically all of the bodily organs is produced, added to which is the great benefit derived from the air currents created by the fan 22 which is driven from the upper shaft 11. At the end of the period of exercise, the power whether manual or mechanical is discontinued, the supports 13 and 14 are permitted to come to rest at their gravity points, and the person who has just taken the exercise steps out of the machine. The exertion put forth by an assistant or assistants at the cranks 15 is, of course, good exercise for and beneficial to such assistant or assistants.

The foot support 13 may be provided with a pair of toe-holds 27, bolted at 28 to the top of said support.

In the present construction, the support 13 is secured by means of a pair of clamps 29 and bolts 30 to a roller which is loosely mounted directly on the lower rod 12 and is similar to the roller 14.

With the exceptions and additions noted below, the same elements are present in the exerciser illustrated in the last two views as in that illustrated in the first two views. In place of the lower crank-arms 10 a pair of large disks 31 is employed, and in place of the upper crank-arms 10 a pair of smaller disks 32 is employed. Rods 12 connect the two pairs of disks 31 and 32, and said rods serve a similar purpose to that of the corresponding rods in the other machine, and function in a similar manner. A chair, consisting of a foot support 33, a seat 34, and a back 35, and a pair of straps 36, are here provided and supported from the rods 12, said foot support being loosely mounted directly on the lower rod 12, and said straps passing through openings 37 in the top of said back and over the roller 14 on the upper rod 12. Projecting from each edge of the chair back 35 is a pin or lug 39 which enters a groove 40 formed in the inner face of each disk 31 to receive such lug, such groove being concentric with the lower rod 12. The office of the lugs 39 is to steady the chair as the latter is actuated by the mechanism which carries it. This second construction is provided with the disks 31 and 32 and the chair in order that the same shall be more stable and safer than the other. Here the person taking the exercise seats himself in the chair and grasps the hand support 14, while an assistant or assistants operate the machine by means of one or both cranks 15, or a motor is employed, as in the other case. This appliance may be termed an invalid exerciser. The person in the invalid exerciser receives the benefits to be derived from the motions imparted by the lower rod 12 to the foot support 33, the upper rod 12 to the hand support 14, and the said two

rods to the chair as a whole, and from the air circulated by the fan 22, but is spared practically all effort in obtaining these movements and this extra air supply. The 5 foot support 33 may be provided with toe-holds, similar to the toe-holds 27, if it be deemed necessary.

What I claim as my invention, and desire to secure by Letters Patent, is—
10 The combination, in an exerciser, of a frame, two pairs of alining shafts mounted,

one pair above the other, in said frame, and provided with crank members, foot and hand supports carried by said crank members, said foot support being provided with 15 a back and a seat, and supporting members between said hand support and said back.

NICHOLAS PSZYSTAS.
